JOURNAL BOX LID

George McCormick, San Carlos, Lauren N. Griffith, Oakland, Edward J. Carter, Berkeley, and Austin D. Williams, Sacramento, Calif., and Stephen McCormick and Thornton T. McCormick, Columbus, Tex.; said Griffith, said Carter, said Williams, said Stephen McCormick, and said Thornton T. McCormick, assignors to said George McCormick

Application June 25, 1941, Serial No. 399,718

3 Claims. (Cl. 308—47)

This invention relates in general to journal boxes and has more particular reference to covers or lids for such boxes.

A principal object of the invention is the provision of a simple and economically manufactured lid assembly for a journal box having a separable lid proper and means whereby the lid is readily removable and replaceable.

Another important object of the invention is the provision in a journal box lid assembly of a spring retainer having a key-way for receiving a key formed integral with the replaceable lid and means for removably confining the said key in the key-way to form a unitary structure.

A further important object of the invention is the provision of means formed in the removable lid for receiving an oil resistant, water proof, resilient gasket, which forms a positive tight seal on all surfaces of the journal box opening.

Another important object of the invention is the provision of means in the spring retainer for retaining a hinge pin in proper place by the spring tension of the lid assembly.

Numerous other objects and advantages will be apparent as it is better understood from the following description, which, taken in connection with the accompanying drawings, discloses a preferred embodiment thereof.

In the drawings,

Figure 1 is a front elevation view of a journal box lid assembly embodying the invention;

Fig. 2 is a sectional view of the lid assembly taken on the line 2—2 of Fig. 1, and looking in the direction of the arrows;

Fig. 3 is a rear elevational view of the spring retainer means showing details of construction;

Fig. 4 is a sectional view of the spring retainer means taken on the line 4—4 of Fig. 3, looking in the direction of the arrows;

Fig. 5 is a top edge view of the spring retainer means showing details of the hinge pin receiving means; and

Fig. 6 is a view of the central portion of the replaceable lid showing the flange and pin portion of the lid and spring retainer fastening means.

Referring to the drawings, reference character 7 indicates the usual type of journal box having walls 8, a further description of which is thought unnecessary, as such construction is well-known to those skilled in the art. The journal box is provided with a hinge lug 9 on the top wall thereof to which a journal box lid assembly, designated generally at 10, is hingedly connected by means of a hinge pin 11. The lid assembly com-

prises generally the lid proper 12, a spring retainer 13, and a duplex tension spring 14.

The spring retainer 13 comprises an upper wall or spring housing portion 18, and a lower base portion 19 extending beyond the spring housing portion and inwardly to the center of the lid assembly where it terminates in a relatively thicker and annular pin-receiving portion 21 which has an inner face 22 and an opening 23 for a purpose later to be described. The spring housing portion 18 overlies the coil portions 24 of the torsion spring 14 disposed in recesses or pockets 26 of the lower base portion 19 of the spring retainer 13. The torsion spring 25 is of the usual type provided for resiliently holding the lid assembly 10 in open or closed position. The lever portion 27 of the spring is disposed within a wear plate or roller 28, and the free ends 29 of the spring are positioned on lugs or seats 31 formed on the base portion 19 of the spring retainer 13.

Intermediate the pockets 26 there is formed in the base portion 19 a key-way on slot 32 into which is adapted to extend a key 33 formed integral with the face 34 of lid 12 to facilitate accurate positioning of the lid and the spring retainer and maintain the same in assembled relation. The lid face 34 is provided at its center with a raised, hub-like portion 35 having a pin formed integrally therewith which is adapted to enter the opening 23 in the pin-receiving portion 21 of the base portion 19 of the spring retainer 13. The hub-like portion 35 is provided with a surfact 36 for engagement with the inner face 22 of the pin-receiving portion 21.

As will be noted in Fig. 2, the opening 23 is of greater diameter than the pin 36, and relative movement therebetween is prevented by means of a bushing 37 which is adapted to enter the opening 23 and surround the pin 36. A flange 38 is provided on the bushing 37 which is adapted to contact the flat and annular outer face 39 of the pin-receiving portion 21 and prevent further entrance of the bushing into the opening 23. To maintain the bushing 37, lid pin 36 and spring retainer 13 in the above described assembled relation, a bore 41 is provided in the free end of the pin 36 into which is forced a pin 42, thus forming a unit of simple construction.

To remove the lid 12, it is necessary only to drive the pin 42 from the bore 41, remove the bushing 37 and withdraw the pin 36 from the opening 23 and the key 33 out of the key-way 32 in the spring retainer 13. A new lid may be installed merely by reversing the above process. It

will be noted that the lid 12 is entirely separable and removable from the spring retainer 13, thereby permitting repair or replacement of the lid 12 without the necessity of removing the spring retainer 13 from the journal box 7.

The lid 12 is provided with the usual annular and inwardly projecting flange 43, and adjacent thereto at the point of contact or engagement with the faces of the walls of the journal box 7 is also provided with a dovetail slot or groove 44 adapted to receive a sealing gasket 45 which may consist of any oil, water and freeze resistant, resilient material, such as "Corprene" which is used in the present instance. The seal 45, which is cemented in the slot or groove, projects slightly therefrom so as to contact the end faces of the journal box walls, thereby providing a positive seal throughout the entire circumference of the opening; such seal being vastly superior to the metal to metal contact heretofore obtained in journal box and lid constructions, and eliminates the usual jar and shock attendant upon closing the box.

The spring retainer 13 is provided with axially spaced bearing-forming ears 48, which in the applied position of the retainer straddle the hinge lug 9. Opening through each ear 48 is a bore 49 to permit insertion of the hinge pin 11. Each bearing ear additionally is formed with a rearward offset 50 (see Figs. 2, 4 and 5) which opens through the inner end of each bearing, but not through the outer end, thus leaving a shoulder 51. The spacing between the shoulders 51 is just slightly greater than the length of the hinge pin 11, which will thus drop into the offsets (as in Fig. 5) and thus be retained against endwise movement by the shoulders 51. With the spring 14 urging the retainer outwardly away from the hinge lug 9, the hinge pin will be held with its ends in the offsets 50.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a journal box lid assembly, a unitary spring retainer having a base portion and a hood portion, a torsion spring disposed wholly within

said base portion and said hood portion and carried by said base portion, means formed on said spring retained for hingedly connecting said spring retainer and said journal box, a lid member separable from said spring retainer and said journal box and having a pin provided with a bore extending centrally therefrom and a lug struck up from said lid at one end thereof, a plurality of apertures formed in said base portion of the spring retainer for reception of said pin and said lug, a bushing adapted to embrace said pin, and means for removably maintaining said spring retainer, said lid member, and said bushing in assembled relation.

2. In a journal box lid assembly, a spring retainer having a base portion and a hood portion and hingedly connectable to a journal box, the said base portion being provided with upper and lower apertured portions, a separable lid member having a pin formed integrally therewith and extending centrally therefrom for projection through the lower apertured portion of the said base portion in assembled relation of the retainer and lid, removable means for retaining the pin and retainer in assembled relation, and means also formed integrally on said lid member for entrance into said upper apertured portion to facilitate accurate positioning of said lid member with respect to said spring retainer.

3. In a journal box lid assembly, a unitary spring retainer hingedly connectable to a journal box and having a base portion provided with upper and lower apertured portions, a separable lid member having an annular portion for cooperation with the lower extremity of said base portion and having a pin formed integrally therewith and extending centrally therefrom for projection through the lower apertured portion in assembled relation of the retainer and lid, removable means for retaining the lid member and retainer in assembled relation, and additional inter-engaging means formed on said lid member for engagement with the upper aperture of said retainer to facilitate accurate positioning of the parts and permit limited relative movement therebetween.
